poration of Delaware

Application July 22, 1937, Serial No. 154,941

14 Claims. (Cl. 200—121)

My invention relates, generally, to circuit interrupters and it has particular relation to mounting devices for fuse housings and fuse links, such as are disclosed in my copending application, Serial No. 144,789, filed May 26, 1937, and assigned to the assignee of this application, which are particularly well suited for connection in the low voltage high current circuit of a distribution transformer, although they are not limited for use in this particular application.

In my copending application I have disclosed a fuse link that comprises a fusible element interconnecting a pair of terminals to each of which is connected a flexible lead for the purpose of connecting the link in a circuit. The link, in one embodiment, is arranged for mounting in a tubular fuse housing that vents at each end when the link blows. The flexible leads extend out of the ends of the housing and are clamped around tubular terminals at these ends which not only provide circuit connections thereto but also provide for venting the fuse housing. Since the fuse housing vents in opposite directions on blowing of the fuse link, it is unnecessary to provide a mounting that is capable of withstanding relatively great stress for the reason that the reaction forces are neutralized. This is particularly advantageous when the stresses set up under some short circuit conditions are considered. In order to obtain a selective action with respect to fuse devices connected in the high voltage low current circuit of the distribution transformer, it is necessary to provide fuse devices in the secondary circuit that are capable of operating continuously on flow of current close to the minimum fusing current without blowing and without causing any change in the operating characteristics of the fuse devices that would alter their time-current characteristics. Under such operating conditions the temperature of the fusible element of the fuse device should be relatively low so that the adjacent housing and supporting structure will not be injured by excessive heat. For this purpose, according to my copending application, I have provided a composite fusible element in a fuse link that comprises a low melting point core and a high melting point sheath therefor. For example, the core may be composed of tin and the sheath may be composed of silver. By combining the operating characteristics of two such metals it is possible to provide a fuse link that is capable of operating continuously at a relatively low temperature close to its minimum fusing current and at the same time its time-current characteristic remains substantially unchanged.

The object of this invention, generally stated, is to provide mountings for certain of the fuse 60 housings and links disclosed in my copending ap-

plication that will be simple and efficient in operation and which may be readily and economically manufactured and installed.

An object of my invention is to detachably mount a fuse housing that vents both ends in such manner that venting thereof will not be interfered with and at the same time provides for connecting the device in an electric circuit.

A further object of my invention is to provide a fuse construction which can be refused without hazard to the lineman in which contact resistance and losses between the replaceable fuse link and container or housing therefor, between container and mounting therefor, and between mounting and line conductors are reduced to a minimum.

Another object of my invention is to mount a signal lamp in a novel manner to indicate that a fuse device of the foregoing type has operated.

A further object of my invention is to provide a novel means for clamping and unclamping a tubular terminal of a fuse housing.

A still further object of my invention is to electrically interconnect by a renewable fuse link a pair of line conductors that extend in opposite directions from an insulator mechanically interconnecting them.

Another object of my invention is to provide for testing an overhead electric circuit in which a fuse link has blown to determine if it is safe to replace the blown fuse link.

Still another object of my invention is to provide for mounting a renewable fuse link in a housing intended to be closed at one end and open at the other when the fuse link blows.

Another object of my invention is to provide a novel means for indicating that a fuse link has blown.

Other objects of my invention will, in part, be obvious and in part appear hereinafter.

Accordingly, my invention is disclosed in the embodiments thereof shown in the accompanying drawings and it comprises the features of construction, combination of elements and arrangement of parts which will be exemplified in the description hereinafter set forth and the scope of the application of which will be indicated in the appended claims.

For a more complete understanding of the nature and scope of my invention, reference may be had to the following detailed description taken in connection with the accompanying drawings in which:

Figure 1 is a view, partly in side elevation and partly in section, of one embodiment of my novel mounting structure for fuse housings;

Figure 2 is a view in front elevation of a shunt blade that may be employed in connection with the mounting shown in Figure 1;

Figure 3 is a view, in front elevation, of the

mounting device shown in Figure 1, with the shunt blade in position;

Figure 4 illustrates diagrammatically the circuit connections that may be employed in practicing my invention;

Figure 5 is a view, in front elevation, showing how two of the fuse housing mountings shown in Figure 1 together with the signal lamps therefor may be positioned on a power line pole or the like and connected in the circuit;

Figure 6 is a view, in front elevation, showing how the single mounting shown in Figure 1 may be positioned on a pole and interconnected in a single circuit;

Figure 7 is a view, in side elevation, of another embodiment of my invention in which a pair of line conductors is interconnected mechanically by an insulator and a mounting is provided for receiving a fuse link to interconnect them electrically;

Figure 8 is a view, in bottom plan, of the construction shown in Figure 7;

Figure 9 is a detail sectional view taken along the line 9—9 of Figure 7;

Figure 10 is a longitudinal sectional view of the fuse link housing shown in Figure 7;

Figure 11 is a view, in front elevation, of a device for receiving a fuse link and adapted to check a circuit to determine whether or not it is safe to re-fuse the same;

Figure 12 is a view, in end elevation, of the device shown in Figure 11;

Figure 13 is a detail sectional view taken along the line 13—13 of Figure 11;

Figure 14 is a longitudinal sectional view of a fuse housing arranged to be closed at one end and adapted to receive a fuse link having a flexible lead at each end;

Figure 15 is a view, in bottom plan, of the housing shown in Figure 14; and

Figure 16 is a fragmentary longitudinal sectional view of the housing shown in Figure 14 illustrating how a universal fuse link having only one flexible lead can be mounted therein instead of the fuse link with a flexible lead at each end.

Referring now particularly to Figures 1 and 3 of the drawings, it will be observed that the reference character 20 indicates a fragmentary portion of a power line pole or other suitable support for carrying a generally U-shaped bracket 21 on which is mounted a fuse housing mounting, shown generally at 22. The mounting 22 is arranged to support a fuse housing, shown generally at 23, and to provide electrical connection thereto. The bracket 21 is provided with feet 24 that are suitably apertured for receiving lag screws 25, or the like, for mounting the apparatus on the pole 20.

The mounting 22 comprises a base 26, formed of suitable insulating material such as ebony asbestos, and it is provided with centrally located countersunk apertures for receiving bolts 27 from the front face that are threaded into the bracket 21. By providing for mounting the base 26 midway its ends on the bracket 21, the ends thereof are left free for terminal clamps for receiving the fuse housing 23 as will be presently apparent.

The fuse housing 23, which is adapted to receive a replaceable fuse link, is fully described in my copending application, hereinbefore referred to, and, therefore, only a brief description of it will be set forth herein. Generally, it comprises a fuse tube 30 of insulating material having ferrules 31 threaded on its ends. The ferrules 31

are provided with tubular extensions 32 to permit electrical connection to the device and at the same time provide for venting the interior of the tube 30. The ends of the extensions 32 may be closed by plugs 33, such as corks, that are readily expellable on the generation of pressure within the fuse tube 30 caused by blowing of the fuse link therein. For mounting the fuse housing 23 which vents at both ends, it is necessary to provide suitable clamps at its ends which will not interfere with the venting on blowing of the fuse link.

With a view to mounting the fuse housing 23 in this manner, terminal clamps 34 are provided at the ends of the base 26. The terminal clamps 34 are generally J-shaped having a relatively long arm 35 adjacent the base 26 and a relatively short arm 36 spaced therefrom between which the extensions 32 of the ferrules 31 are positioned. The terminal clamps 34 are secured to the ends of the base 26 by bolts 37 and 38 that are positioned in suitable counterbored apertures, as shown in Figure 1. It will be observed that the bolts 37 and 38 are threaded into suitably tapped apertures in the relatively long arms 35.

With a view to removably clamping the extensions 32 of the ferrules 31 in position, each of the long arms 35 of the terminal clamps 34 is provided with a groove 41 along its inner surface that connects with an aperture 42 that extends through the lower end thereof. A clamp bolt 43 is slidably mounted in each of the grooves 41 and apertures 42 and at its upper end it is provided with a headed end 44 that is formed by flattening this end and then turning the same over, as illustrated. Wing nuts 45 threaded on the lower ends of the clamp bolts 43 serve to hold the headed ends 44 of the clamp bolts 43 in clamping engagement with the extensions 32.

It is desirable that the rotation of the wing nuts 45 cause a positive movement of the clamp bolts 43 toward and away from the clamping position. For this purpose each of the wing nuts 45 is provided with an integrally formed boss 46 having a circumferential groove 47 therein. The boss 46 extends into a suitable enlarged aperture in the underside of each of the terminal clamps 34 and, as shown, these enlarged apertures are coaxial with the apertures 42. Pins 48, only one of which is shown, extend through the lower ends of the terminal clamps 34 and interfit with the grooves 47 to prevent axial movement of the wing nuts 45. Since longitudinal movement of the wing nuts 45 is prevented, rotation thereof will cause a positive movement of the clamp bolts 43 toward and away from the clamping depending upon the direction of rotation of the wing nuts 45.

The electrical connection with the terminal clamps 34 by line conductors is provided by integrally formed sockets 49 into which set screws 50 are threaded. Obviously, any other suitable clamping means may be provided for securing the line conductors to the terminal clamps 34.

With a view to providing further indication of whether or not the fuse link in the fuse housing 23 has blown, a lamp socket 53 is mounted in the lower leg of the U-shaped bracket 21 and it has positioned therein an indicating lamp 54. The indicating lamp 54 may be of the incandescent type or it may be of the gas filled type or glow discharge type as may be desired. Conductors 55 are provided for connecting the lamp 54 in the lamp socket 53 across the terminals of

the fuse housing 23. As shown the conductors 55 are provided with suitable terminals and, by means of screws 56, only one of which is shown, they are connected to the lower bolts 38 that hold 5 the terminal clamps 34 to the ends of the base 26.

As long as the fuse link in the fuse housing 23 remains intact the lamp 54 is short circuited. However, as soon as the fuse link blows, and some 10 load remains connected across the line, the lamp 54 will be lighted, thereby indicating that the fuse link has blown and should be replaced.

In order to protect the lamp 54 a suitable metallic cap 57 may be provided thereover and secured, as shown, to the underside of the bracket 15 21. The cap 57 is provided with suitable apertures to permit the light rays from the lamp 54 to be visible from the ground to the line inspector. Ordinarily the lamp 54 will be provided with a colored bulb, such as red, so that on becoming 20 lighted it will be readily visible.

In some cases it may be desirable to remove the fuse housing 23 for testing or other purposes and at the same time to provide for continuity of service on the line. For this purpose a shunt 25 blade 58, Figure 2, is provided having a handle 59 formed of molded insulation at one end. The blade 58 is provided with slotted apertures 60 for interfitting with bolts 61 that are threaded into the lower ends of the relatively short arms 30 36 of the terminal clamps 34. Washers 62 are provided on the bolts 61 together with coil compression springs 63. After the shunt blade 58 is in position, the bolts 61 may be tightened to resiliently hold it in position between the washers 35 61 and the short arms 36 of the terminal clamps 34. In this manner the application and removal of the shunt blade 58 is entirely independent of the clamp bolts 43 which serve to removably 40 clamp the fuse housing 23 in position. Once the shunt blade 58 has been clamped in position the fuse housing 23 may be removed without interruption of the circuit.

Figure 6 of the drawings shows the manner in which the fuse housing mounting 22, shown in 45 Figures 1 and 3 of the drawings, is employed. As there shown, line conductors A are dead-ended at the pole 20 by any suitable means. For example, the U-shaped brackets 66 may be employed having spool type insulators 67 carried 50 thereby. The ends of the conductors A may be looped around the insulators 67 and secured, as shown. Jumper connections 68 are provided for interconnecting the line conductors A and the 55 sockets 49 integrally formed with the terminal clamps 34.

In Figure 5 of the drawings I have illustrated the manner in which two of the fuse mountings 22 may be employed in connection with a single phase three-wire circuit comprising a neutral 60 conductor N and conductors A and B. The line conductors N, A and B may be dead-ended at the pole 20 on suitable insulators, such as the spool type insulators 67, that are carried on suitable mounting brackets 71. Two mountings 22 65 are mounted at opposite ends of a suitable base 12, formed of insulating material, that is in turn mounted by a suitable bracket on the pole 20. The jumper connections 68 are provided to interconnect the line conductors A and B with the 70 sockets 49 in their respective terminal clamps 34. These are, in turn, interconnected by the fuse links in the fuse housings 23. A single jumper connector 73 serves to interconnect the line conductors N. Since this is the neutral conductor, it is unnecessary to fuse it.

In Figure 4 of the drawings, the circuit connections that may be employed for practicing the present invention are shown with special reference to a three-wire single phase distribution circuit. The line conductors may be the conductors 5 A, B, and N, shown in Figure 5 and previously described. For energizing these conductors a transformer, shown generally at 75, is provided having a primary winding 76 for connection to a suitable source of single phase alternating current, such as a 60-cycle source. The transformer 75 is provided with a secondary winding 77 the terminals 78 and 79 of which are connected to the line conductors A and B respectively through fuse links 80 and 81. The fuse links 80 and 81 15 may be and preferably are of the type shown in my copending application, hereinbefore referred to, and are contained in the fuse housing 23, shown in Figures 1 and 3 of the drawings and described hereinbefore. The secondary winding 20 77 is provided with a mid-tap 82 for direct connection to the neutral conductor N. The distribution circuit may be arranged for operation at the standard voltage of 230 volts between the conductors A and B and 115 volts between either 25 of these conductors and the neutral conductor N. Typical load devices, such as the motors 83 and 84, may be connected between the conductors A and B and the neutral conductor N, as shown. On the flow of fault current on either of the 30 conductors A or B, the corresponding fuse link 80 or 81 will blow. Assuming that some load device, such as either of the load devices as 83 or 84 remains connected to the circuit, then the indicating lamp 85 or 86 will be lighted as soon as 35 the corresponding fuse link 80 or 81 blows. The indicating lamps 85 and 86 may be of the type shown at 54 in Figures 1 and 3 of the drawings and described hereinbefore. The lighting of one or both of these lamps indicates that the fuse link 40 corresponding thereto has blown and should be replaced in order to restore service.

In some installations it may be undesirable to dead-end the line conductors at a pole. It may be preferable to dead-end them intermediate the 45 poles. For such an installation, the construction shown in Figures 7, 8, 9, and 10 may be employed with advantage. As there shown, the line conductors A are dead-ended by means of a single insulator 89 through which they are looped in 50 suitable apertures at right angles to each other, the ends being clamped by suitable clamps 90. The line conductors A are thus mechanically interconnected but, because of the insulator 89, they are insulated from each other.

The conductors A may be electrically interconnected by a replaceable fuse link 91 that is provided with flexible leads 92 at its ends. The fuse link 91 may be of the type described in detail in my copending application, hereinbefore referred to. The ends of the flexible leads 92 may be secured, as by clamps 93, to support members 94, in the form of copper rods, the ends of which are off-set so that they will be parallel with the undersides of the line conductors A for clamping 65 thereto by suitable clamps 95.

With a view to protecting the fuse link 91 from the weather, a fuse housing 96 is provided. As shown, longitudinally extending apertures 97 are provided near the top surface of the housing 70 96 and they are of such diameter as to provide a snug fit with the opposing ends of the support members 94 which are secured therein by transverse pins 98. As shown in Figure 9 of the drawings, the pins 98 are disposed in suitable 75

apertures, the ends of which are counterbored for receiving a suitable plastic material 99 for filling the same.

The fuse link 91 is mounted in a suitable longitudinally extending aperture 100 adjacent the lower surface of the housing 96 which terminates in enlarged apertures 101. This construction with the enlarged apertures 101 is provided to insure that the gases generated on blowing of the fuse link 91 will be free to escape from the housing 96 in opposite directions with one result being that the radial pressure components on the walls of the aperture 100 will be minimized. There will then be substantially no reaction between the housing 96 and the support members 94 therefor.

If, after blowing of a fuse, a fault still exists on the circuit in which the fuse construction and mounting shown in Figures 7, 8, 9, and 10 is employed, it is dangerous for the lineman to replace the blown fuse link. It will be obvious, under such conditions, that the new fuse link will immediately blow and, since the lineman is required to be in close proximity to the housing 96 for replacing the fuse link, it is possible that he may be severely burned.

With a view to obviating this dangerous condition the circuit checking apparatus shown in Figures 11, 12 and 13 may be employed. By the use of this apparatus, it is possible to determine whether the fault condition still persists. This apparatus comprises the device shown generally at 104 which includes a tubular insulating member 105 formed of a material such as "Bakelite." Intermediate its ends a fitting 106 is provided for receiving the threaded end of a handle 107 that is formed of a suitable insulating material such as wood. The tube 105 is arranged for receiving a fuse link 108 therein having flexible leads 109 at its ends. The link 108 may be similar to the link 91 shown in Figures 7 and 8 of the drawings and described hereinbefore.

As shown, the fuse link 108 is positioned inside of the tube 105 midway its ends and the flexible leads 109 are positioned between spring clips 110 and 111 that form extensions of a generally U-shaped contact prong 112. The contact prong 112 is formed of conducting material such as phosphor bronze and the upper portion is held in position by a suitable rivet 113 and spacers 114. Rivets 115 serve to hold the contact prongs 112 to the ends of the tube 105. The end 116 of the spring clip 110 is turned upward a slight amount in order to facilitate the positioning of the flexible lead 109 between it and the spring clip 111.

Before replacing the fuse link, such as the fuse link 91 shown in Figures 7 and 8, the lineman places a fuse link, such as the fuse link 108, in the tube 105 and then by grasing the handle 107 moves the contact prongs 112 into contact engagement with the support members 94. If the fault still persists, the fuse link 108 will be immediately blown but, since it is spaced some distance away from the lineman, he will not be harmed. The circuit can then be inspected to locate the fault and to remove the same before the circuit is re-fused.

There are some installations in which it is desirable to provide for out-of-doors mounting of a fuse link having a flexible lead at each end in a housing, one end of which is adapted to remain closed when the fuse link blows. Such a fuse housing is shown generally at 119 in Figure 14 of the drawings. This housing 119 is arranged

for mounting in a vertical position and is adapted to receive a fuse link 120 having flexible leads 121 and 122 at its ends. The fuse link 120 is of the type that is shown and described in my co-pending application, hereinbefore referred to.

The housing 119 comprises an outer tube 124, formed of a material such as "Bakelite," and an inner tube or liner 125 formed of a material such as fiber that is capable of evolving an arc extinguishing medium on blowing of the fuse link 120.

At its upper end the housing 119 is provided with an upper ferrule 126 to which may be connected a terminal fitting 127 for receiving a line conductor. A pin 128 extends transversely through the shank of the terminal fitting that projects into the ferrule 126 for securing it in position.

At its upper end the upper ferrule 126 is provided with a threaded reduced end portion 129 to form a shoulder 130 for receiving the end of the flexible lead 121. The reduced end portion 129 is provided with a longitudinally extending aperture 131 that constitutes an extension of the bore of the fiber liner 125 and it is provided with a slotted opening 132 through which the flexible lead 121 may be positioned to permit its being placed around the reduced end portion 129 and on the shoulder 130. A cap 133 having a shoulder 134 is threaded on the reduced end portion 129 for closing the upper end of the housing 119 and securing the flexible lead 121 in position between the shoulders 130 and 134. The cap 133 is provided with a depending flange 135 that overlaps the shoulder 130. A pin 136, extending transversely through the upper ferrule 126 and a portion of the outer tube 124, serves to securely hold the upper ferrule 126 on the housing 119. Since the cap 133 is threaded on the ferrule 126, the upper end of the housing 119 is closed and ordinarily will remain closed on blowing of the fuse link 120.

The lower end of the housing 119 is arranged to be open so that free venting downwardly is permitted on blowing of the fuse link 120. At this lower end a combined lower ferrule and housing 139 is provided having a depending skirt 140. A pin 141 extending transversely through the ferrule 139 and a portion of the outer tube 124 serves to secure the former to the latter. A terminal socket 142 is integrally formed with the skirt 140 and the flexible lead 122 is securely clamped therein by a set screw 143. Connection to the lower ferrule and housing 139 is provided by a terminal fitting 144 the shank of which projects into the skirt 140 and is secured therein by a pin 145.

It is desirable to provide an indication that the fuse link 120 has blown. For this purpose an indicator arm 146 having an integrally formed boss 147 is located within the skirt 140 and is rotatably mounted on a transverse pin 148 that extends between the depending sides thereof. At its outer end the indicator arm 146 is provided with a target 149 that is circular in shape and has shallow sockets 150 on opposite sides thereof for receiving indicator discs 151. These discs 151 may be formed of red prismatic glass or the like which makes them readily visible. The discs 151 are of particular value at night for they can be readily seen by flashing a light on one or the other of them and thereby a blown fuse link can be quickly detected by a lineman from his car or truck located some distance away. He may

use either a flashlight or a spot light to pick up the discs 151 as will be readily understood.

5 A mechanical connection between the flexible lead 122 and the indicator arm 146 is provided by a pawl 152 that is mounted for rotation on a pin 153 which extends transversely through the skirt 140. The outer end 154 of the pawl 152 is grooved to receive the flexible lead 122. The pawl 152 is provided with a tooth 155 for interfitting 10 with a notch 156 in the boss 147.

When the fuse link 120 has been placed in the housing 129, as shown in Figure 14 of the drawings, and the flexible lead 122 drawn up tightly and secured by the set screw 143, the indicator 15 arm 146 will be held in the position shown and the target 149 with the discs 151 therein will be concealed from view by the skirt 140. As soon as the fuse link 120 blows, the pawl 152 is no longer restrained and the indicating arm 146 20 is free to rotate downwardly carrying with it the target 149. Casual inspection of the device will reveal that the fuse link 120 has blown since the discs 151 of the target 149 will then be clearly visible.

25 In order to apply a spring tension to the fuse link 120 and to insure that the pawl 152 will be moved when the fuse link blows, a coil compression spring 157 may be interposed between the back side of the pawl 152 and the adjacent inner 30 surface of the skirt 140. A boss 158, formed with the pawl 152, serves to center the spring 157.

As shown in Figure 16 of the drawings, the upper ferrule 126 and the cap 133 are also arranged to receive a universal fuse link 120', the 35 construction of which is similar to that of the fuse link 120 and which is described in detail in my copending application hereinbefore referred to. Generally, the difference between the fuse links 120 and 120' resides in the omission of the upper flexible lead 121 from the former and the provision of a button terminal 160 on the latter. The upper end of the insulating sleeve 40 of the fuse link 120' is crimped or otherwise secured to a suitable terminal onto which the button terminal 160 may be threaded, as described 45 in my said copending application.

It will be observed that the radially extending flange of the button terminal 160 is positioned between the upper face 161 of the end portion 129 50 and the under face 162 of the cap 133. The space between the shoulders 130 and 134 is sufficient to permit the cap 133 to be screwed tightly onto the button terminal 160.

55 In this manner it is possible to employ the same upper terminal construction for the housing 119 to receive either type of fuse link without requiring any change to adapt it for one or the other. Consequently, the same housing 119 can be used for receiving many of the replaceable fuse links 60 that are available in the open market.

Since certain changes may be made in the foregoing constructions and different embodiments of the invention may be made without departing from the scope thereof, it is intended that all 65 matter shown on the accompanying drawings are described hereinbefore shall be interpreted as illustrative and not in a limiting sense.

I claim as my invention:

1. A circuit interrupting means comprising, in 70 combination, a fuse housing having metal ferrules adjacent its ends adapted to be interconnected by a renewable fuse link therein, said ferrules having openings for venting said housing at both ends on blowing of said fuse link, a terminal 75 clamp removably attached to each ferrule in such

position as not to interfere with the venting of said housing from both ends, conductor receiving means on each terminal clamp, a shunt member, and means for detachably clamping said shunt member to each terminal clamp for inter- 5 connecting the same.

2. Circuit interrupting means comprising, in combination, an insulating base; a pair of clamp jaws mounted in parallel spaced apart relation on said base each comprising a generally J- 10 shaped metal clamp member having a groove extending along substantially the entire length of the inner surface of its longer arm and an aperture aligned therewith and extending through its base, clamp means having a headed end slidably 15 mounted in said groove and aperture, and a conductor receiving socket; and a tubular fuse housing having metal ferrules adjacent its ends adapted to be interconnected by a renewable fuse link therein, said ferrules having openings for 20 axially venting said housing at both ends on blowing of said fuse link and arranged and adapted to be clamped between said headed ends of said clamp means and the shorter arms of said J-shaped clamp members in such position as not 25 to interfere with the axial venting of said housing from both ends.

3. A terminal connector for detachably receiving a tubular terminal of a fuse housing adapted for axial venting at both ends on blowing of a 30 fuse link therein comprising, in combination, a generally J-shaped metal clamp member having a groove extending along substantially the entire length of the inner surface of its longer arm and an aperture aligned therewith and extending 35 through its base, a clamp rod having a headed end slidably mounted in said groove and aperture, means for adjustably positioning said clamp rod in said groove for clamping said tubular terminal between its headed end and the shorter arm of 40 said clamp member with the bore thereof free to vent outwardly, and means for securing a line conductor to said clamp member.

4. A terminal connector for detachably receiving a tubular terminal of a fuse housing adapted for axial venting at both ends on blowing of a 45 fuse link therein comprising, in combination, a generally J-shaped metal clamp member having a groove extending along substantially the entire length of the inner surface of its longer arm 50 and an aperture aligned therewith and extending through its base, a clamp rod headed at one end and threaded at the other slidably mounted in said groove and aperture, a nut on said threaded end of said rod, means rotatably mounting said 55 nut on said clamp member and preventing relative longitudinal movement whereby said clamp rod is moved in said groove and aperture on rotation of said nut in either direction to clamp and unclamp said tubular terminal between said 60 headed end and the shorter arm of said clamp member with the bore thereof free to vent outwardly, a socket portion for receiving a line conductor integrally formed with said clamp member, and means for securing said line conductor 65 in said socket portion.

5. For combination with a pair of line conductors one constituting a continuation of the other and disposed in insulated relation; a pair 70 of support members formed of conducting material, adapted to be connected at one end to said line conductors and extending toward each other in spaced apart relation at the other end; a fuse housing having an aperture extending inwardly from each end for receiving the spaced 75

apart ends of said support members therein and an aperture extending longitudinally therethrough, a fuse link in said longitudinally extending aperture having flexible leads extending out 5 of the ends thereof, and means for securing said flexible leads to said support members, thereby electrically interconnecting said line conductors.

6. For combination with a pair of line conductors extending along substantially a straight 10 line and insulated from each other; a pair of substantially rigid support members formed of conducting material, adapted to be clamped at one end to said line conductors and extending toward each other with the ends spaced apart; a 15 fuse housing having an aperture extending inwardly from each end for receiving therein said spaced apart ends of said support members and an aperture extending longitudinally therethrough, a fuse link in said longitudinally extending 20 aperture having flexible leads extending out of its ends, and means for clamping said flexible leads to said support members, thereby electrically interconnecting said line conductors.

7. In an electric distribution system, in combination, an insulator, a pair of line conductors having the adjacent ends looped over said insulator thereby being electrically insulated from each other and extending in opposite directions therefrom; a pair of rod-like conductors having off- 25 set end portions, means clamping said end portions to the under sides of said line conductors with the other end portions extending substantially parallel thereto and the ends thereof spaced apart, a block of insulation having an aperture 30 extending longitudinally inwardly from each end for receiving therein said spaced apart end portions of said rod-like conductors and an aperture extending longitudinally therethrough having enlarged end portions, means securing said rod-like 35 conductors in said block of insulation, a fuse link in said longitudinally extending aperture having flexible leads extending out of its ends, and means clamping said flexible leads to the under sides of 40 said rod-like conductors, thereby electrically interconnecting said line conductors.

8. A fuse housing for mounting out-of-doors in a vertical position and adapted to receive a renewable fuse link having flexible leads at its ends comprising, in combination, a fuse tube, a 45 terminal at the upper end of said fuse tube adapted to receive one flexible lead of said fuse link, means closing the upper end of said fuse tube and capable of keeping the same closed on blowing of said fuse link, a closure at the lower end of 50 said fuse tube opening downwardly, means on said closure for receiving the other flexible lead of said fuse link, and indicating means within said closure including a target controlled by said fuse link, said target dropping below said closure on 55 blowing of said fuse link.

9. A fuse housing for mounting out-of-doors in a vertical position and adapted to receive a renewable fuse link having flexible leads at its ends comprising, in combination, a fuse tube, a terminal at the upper end of said fuse tube adapted 60 to receive one flexible lead of said fuse link, means closing the upper end of said fuse tube and capable of keeping the same closed on blowing of said fuse link, a metal housing secured to the lower 65 end of said fuse tube having a flared out portion opening downwardly, means for connecting the other flexible lead of said fuse link to said hous-

ing, a target rotatably mounted in said housing, a pawl rotatably mounted in said housing and cooperating with said other flexible lead and said target to restrain the latter as long as said fuse link remains intact, and resilient means 5 biasing said pawl into engagement with said other flexible lead.

10. In a circuit interrupter, in combination, a fuse tube adapted to be mounted in a substantially vertical position for receiving a fuse link, 10 a housing at the lower end of said fuse tube opening downwardly, and an indicator held in a relatively obscure position within said housing until said fuse link operates, said indicator being adapted to move out of said housing to a position 15 where it can readily be seen on operation of said fuse link.

11. In a circuit interrupter, in combination, a fuse tube adapted to be mounted in a substantially vertical position for receiving a fuse link, 20 a housing at the lower end of said fuse tube opening downwardly, and an indicator pivotally mounted on said housing and held therein in a relatively obscure position by said fuse link and biased downwardly, said indicator being released 25 for downward movement to a position where it is readily visible on operation of said fuse link.

12. In a circuit interrupter, in combination, a fuse tube adapted to be mounted in a substantially vertical position for receiving a fuse link 30 having a flexible lead extending from at least one end thereof, terminal means at the upper end of said fuse tube for receiving the other end of said fuse link, a metallic housing at the lower end of said fuse tube opening downwardly and 35 adapted to receive said flexible lead, and an indicator pivotally mounted on said housing and held therein in a relatively obscure position by said fuse link and biased downwardly, said indicator being released for downward movement to a 40 position where it is readily visible on operation of said fuse link, the biasing action applied to said indicator tensioning said fuse link.

13. In a circuit interrupter, in combination, a fuse tube adapted to be mounted in a substantially vertical position for receiving a fuse link, 45 a housing at the lower end of said fuse tube opening downwardly, and indicator means including a distinctively colored reflecting member held thereby in a relatively obscure position within 50 said housing until said fuse link operates, said indicator means being adapted to move said reflecting member out of said housing to a position where it can receive and reflect light rays impinging thereon so that the occurrence of a 55 blown fuse link can be readily detected from a distance.

14. In a circuit interrupter, in combination, a fuse tube adapted to be mounted in a substantially vertical position for receiving a fuse link, 60 a housing at the lower end of said fuse tube opening downwardly, and indicator means including a red glass member held thereby in a relatively obscure position within said housing until said 65 fuse link operates, said indicator means being adapted to move said red glass member out of said housing to a position where it can receive and reflect light rays impinging thereon so that the occurrence of a blown fuse link can be readily detected from a distance.
